SHUTTLE MECHANISM

Axel Folke Carlson, Stockholm, Sweden, assignor
to The Reece Button Hole Machine Company,
Boston, Mass., a corporation of Maine

Application November 26, 1937, Serial No. 176,414

6 Claims. (Cl. 112—232)

This invention relates to the thread-handling devices of lock-stitch sewing machines, and more particularly to a novel shuttle mechanism thereof.

5 It is among the objects of the present invention to provide a novel drive for a rotary shuttle which permits the unobstructed passage of a non-twisted thread loop around the shuttle.

10 It is another object of the present invention to provide novel structure which prevents the escape of the bobbin from its support on the shuttle as well as rotation of the bobbin together with the shuttle, without interfering with the passage of a non-twisted thread loop around the shuttle. 15

15 The foregoing and other objects of the present invention, together with means whereby the latter may be carried into effect, will best be understood from the following description of an illustrative embodiment thereof shown in the accompanying drawings. The particular mechanism described and shown is, however, being chosen for purposes of exemplification merely, as it will be obvious to those skilled in the art 20 that the invention, as defined by the claims hereunto appended, may be otherwise embodied without departure from the spirit and scope thereof.

In said drawings:

30 Fig. 1 is a front elevation, partly in section, of a shuttle mechanism which embodies the present invention. Fig. 2 is a section through the shuttle mechanism, taken substantially on the line 2—2 of Fig. 1.

35 Fig. 3 is a section taken substantially on the line 3—3 of Fig. 1.

Fig. 4 is a perspective view of the shuttle.

Fig. 5 is a perspective view of the bobbin case which is supported by the shuttle.

40 Fig. 6 is a perspective view of a detail of the present shuttle mechanism.

Fig. 7 is a perspective view of certain cooperating elements of the shuttle mechanism.

45 Fig. 8 is another perspective view of certain cooperating elements of the shuttle mechanism.

Figs. 9 and 10 are front elevations of the cooperating elements illustrated in Fig. 7, showing said elements in different positions of cooperation, however.

50 Fig. 11 is a sectional view of a modified shuttle mechanism.

Referring to the drawings and more particularly to Figs. 1, 2 and 3, the reference numeral 20 designates the horn of any conventional lock-stitch sewing machine (not shown). Mounted

on the horn 20 by means of screws 21 is a shuttle support 22, provided with a central opening 23 which is counter-bored at 24 to form the race for a shuttle 25. A ring member 26 is mounted on the shuttle support 22 by means of bolts 27 5 and is adapted to retain the shuttle 25 in its race. The shuttle 25, which is substantially dish-shaped in cross section and approximates segmental shape in front elevation, as can be observed in Fig. 4, is provided with a peripheral 10 rim 28 which rests in the race 24 (Fig. 3). The shuttle is also provided with diametrically opposite slots 29 which are adapted to receive the projecting driving ends 30 of a lever 31, pivoted at 32 centrally between its ends to a shaft 33 15 20 which has one end journaled in a bearing 34, formed integral with or mounted in any suitable manner on the horn 20 of the sewing machine. Shaft 33 may be driven in any suitable manner (not shown) in timed relation with the needle 25 reciprocation. Inasmuch as the illustrated shuttle requires the greater part of one revolution for the passage of a thread loop therearound, the shuttle is so driven that it will make two revolutions to each needle reciprocation so 25 that the take-up device (not shown) may perform its operation and the needle may go through its necessary motions for casting a new loop 1 during the intervening time period between successive passages of loops around the shuttle. 30 More particularly, the entire lever 31 is straddled by a bifurcated transverse head 35 of the shaft 33 which prevents any appreciable bending of said lever 31 and, hence, not only maintains the driving ends 30 thereof in perfect alignment with 35 their respective slots 29 in the shuttle but also renders the pivot 32 free from any bending stresses so that said pivot is subjected only to shearing stresses when transmitting the driving force from the shaft 33 to the lever 31. Inasmuch as the ends 30 of the lever 31 are adapted 40 alternately to drivingly engage the shuttle 25 and to rotate the same continuously and at uniform speed, it is of the greatest importance that said driving ends 30 are in perfect alignment with their respective slots 29 of the shuttle 45 while intermittently out of engagement therewith, and that they fit rather accurately into said slots 29 to avoid any lost motion between the shuttle 25 and the driving lever 31. The other end of the shaft 33 may in any suitable manner be rotatably mounted in the sewing machine and held axially immovable so that an annular shoulder 36 of said shaft is in permanent engagement with the machined face 37 of the bearing 34. 50 55

The ends 30 of the lever 31 are in permanent cooperation with an annular cam 38 which is mounted in any suitable manner on the bearing 34 concentrically to the shaft 33. The active surface 39 of the cam 38 is a plane surface which extends at the inclination shown in Fig. 3 with respect to the axis of the shaft 33. More particularly, the inclination of the cam surface 39 is such that at least one of the depending ends 10 30 of the lever 31 projects into its respective slot 29 in the shuttle irrespective of the angular position of said lever, and that said ends 30 alternately move into and out of driving engagement with their respective slots 29. The continuous drive of the shuttle is assured inasmuch as either end 30 of the lever 31 remains in driving engagement with the shuttle until the other end has moved into driving engagement therewith. The angular disposition of the cam 38 20 29 is such that each end 30 of the lever 31 is in driving engagement with its respective slot 29 in the shuttle substantially during rotation through the angular distance A (Fig. 1), and is out of driving engagement with its respective slot 25 29 during rotation through the remaining angular distance. Hence, after the hook 40 of the rotating shuttle 25 has entered the thread loop l, previously cast into the path of rotation of said hook by the axially reciprocating needle 42 on 30 slight recession from its lowermost position into the position shown in Fig. 3, the rear leg 43 of said loop may pass along the rear surface 44 of said shuttle and across a presently disengaged slot 29 thereof before the corresponding end 30 35 of the lever 31 reenters said slot. By the time the take-up device (not shown) of the sewing machine becomes operative after the loop l has been substantially passed around the shuttle, the other end of the lever 31 has already been moved 40 out of driving engagement with its respective slot 29 in the shuttle and permits the withdrawal of said rear leg 43 of the loop from the shuttle between the latter and said other end of the driving lever 31. Consequently, the present 45 shuttle drive does not require a twist in the loop l in order that the same may pass around the shuttle without interference from the shuttle drive.

Projecting from the shuttle 25 is an eccentric pin 45 which rotatably receives the hollow shank 46 of a bobbin case 47 that holds the usual bobbin (not shown). The bobbin case 47 is provided with three angularly spaced, radially projecting lugs 48, 49 and 50. The lugs 48 and 50 are substantially diametrically opposite each other and serve to hold a cover (not shown) which is preferably hinged in a notch 51 of the lug 48 and provided with a suitable extension that snaps into a notch 52 of the other lug 50. The lugs 48 55 and 49 are also provided with surfaces 53 and 54, respectively, which are inclined with respect to the axis of the bobbin case as shown in Figs. 5, 7, 9 and 10. Adapted to cooperate with these inclined surfaces 53, 54 are two correspondingly inclined surfaces 55 and 56, respectively, of a member 57 (Figs. 1, 2 and 6) which is mounted on the shuttle support 22 by the above mentioned bolts 21. More particularly, the surfaces 55 and 56 of the member 57 project into the path of 60 rotation of the lugs 48 and 49, respectively, of the bobbin case in the normal direction of rotation of the shuttle 25 as can be best observed in Fig. 7. Although the bobbin case 47 is rotatably supported on the shuttle 25, it is nevertheless prevented from rotating together with the shuttle by the 70

surfaces 55 and 56, respectively, of the member 57. Inasmuch as the bobbin case 47 is mounted on the eccentric pin 45 of the shuttle, the former is bodily moved during rotation of the shuttle 25. Due to the presence of the surfaces 55 and 56 5 of the member 57, the bodily motions of the bobbin case are alternate rocking motions in opposite directions about the surfaces 53 and 54, respectively, of the bobbin case. Therefore, movement of the bobbin case 47, as caused by the eccentric pin 45, results in alternate engagement and disengagement between the surfaces 53, 55 and 54, 56, respectively, of the bobbin case and the member 57, respectively, as can be readily understood. Consequently, gaps 58 and 59 alternately open 15 and close between the surfaces 53, 55 and 54, 56, respectively, of the bobbin case 47 and member 57 (see Figs. 9 and 10). In the angular position of the shuttle illustrated in Fig. 9, the eccentric pin 45 assumes an angular position in which it 20 holds the bobbin case 47 at the end of one of its counter-clockwise rocking motions about the engaged surfaces 53, 55 of the bobbin case 47 and member 57, respectively, as a floating fulcrum, with the result that the gap 58 is entirely closed 25 and the gap 59 is of maximum width. While the gap 59 is substantially open, the front leg 62 of the thread loop l is gradually deflected through said open gap 59 by a skirt 60 which is integral with the shuttle 25 and has a thread-deflecting 30 edge 61 (Figs. 4, 7 and 8) that gradually spreads said loop so that said forward leg 62 passes through the gap 59 and to the front of the covered end 63 (Fig. 7) of the bobbin case 47. Upon continued rotation of the shuttle 25 from the 35 position shown in Fig. 9 to that shown in Fig. 10, the eccentric pin 45 first causes a rocking motion of the bobbin case 47 in clockwise direction as viewed in Fig. 9 and about the engaged surfaces 53, 55 of the bobbin case 47 and member 57, respectively, as a floating fulcrum until the gap 59 is completely closed. Thereafter, the eccentric pin 45 again rocks the bobbin case counter-clockwise as viewed in Fig. 10 about the then engaged surfaces 54, 56 of the bobbin case and member 57, 45 respectively, as a floating fulcrum, with the result that the gap 58 gradually opens until it reaches its maximum width when the shuttle 25 arrives substantially at the position shown in Fig. 10. At this time, the loop l has passed sufficiently far 50 around the shuttle to permit any conventional take-up device (not shown) to start withdrawal of the loop l from the shuttle, whereupon the forward leg 62 of said loop passes through the open gap 58. Upon continued clockwise rotation of the 55 shuttle from the position shown in Fig. 10, the open gap 58 is first gradually closed again, and the bobbin case 47 is thereafter rocked counter-clockwise about the then engaged surfaces 53, 55 of the bobbin case 47 and member 57, respectively, 60 as a floating fulcrum, with the result that the gap 59 gradually reopens to provide for the passage of the forward leg 62 of a new loop l therethrough substantially when the shuttle reaches again the position shown in Fig. 9. Inasmuch as the 65 present shuttle makes two revolutions to each reciprocation of the needle, it is obvious that a thread loop is passed around the shuttle on alternate revolutions only of the latter. However, the gaps 58 and 59 open and close during each revolution of the shuttle to provide passage for the forward leg 62 of a loop. It is, therefore, obvious that the present bobbin case 47 and cooperating member 57 can be used together with a shuttle that makes only one revolution to each needle 70 75

reciprocation and, consequently, passes a thread loop around the bobbin on each revolution. It can also be understood from the foregoing description that at least one of the inclined surfaces 53, 54 of the bobbin case is in engagement with its respective surface 55, 56 of the member 57 in any angular position of the shuttle, with the result that the surfaces 55, 56 of said member 57 not only prevent rotation of the bobbin case 10 together with the shuttle at all times, but also frictionally retain said bobbin case on its supporting pin 45 regardless of whether the shuttle rotates or is at rest. The sliding friction between the eccentric pin 45 of the rotating shuttle 15 and the hollow shank 46 of the bobbin case drags the latter about said pin 45 in the direction of rotation of the shuttle so that one of the surfaces 53, 54 of said bobbin case is urged into engagement with its respective surface 55, 56 of the stationary member 57, depending on the angular disposition of the eccentric pin 45 and, consequently, of the shuttle 25. Moreover, the mass of the lugs 49 and 50 of the bobbin case is considerably greater than that of the lug 48, and it 25 will be noticed particularly in Fig. 7 that the greater mass of the lugs 49 and 50 is disposed at one side of a vertical plane through the center axis of the bobbin case. This greater mass has a clockwise movement of rotation about the axis 30 of the bobbin case which forces the latter into engagement with the member 57. Thus, the frictional resistance between the eccentric pin 45 and the bobbin case 47 and the explained movement of rotation of the lugs 49 and 50 combine 35 frictionally to retain said bobbin case on its supporting pin 45, regardless of whether the shuttle rotates or is at rest. The bobbin case 47 is furthermore positively retained on the eccentric pin 45 of the shuttle by a lug 70 of the member 57 40 (Fig. 6) in conjunction with the inclined surfaces 55 and 56 of said member 57. It can be observed in Fig. 1, that slight counter-clockwise rotation of the bobbin case 47 away from the surfaces 55, 56 of the member 57, for instance 45 on manual removal of the bobbin from said case 47, immediately brings the bobbin case into a position in which said lug 70 is in the path of axial removal of the former from its supporting pin 45. Thus, the member 57 performs two separate functions, to wit, preventing rotation of the bobbin case 47 together with the shuttle, and preventing axial escape of said bobbin case from its supporting pin 45 on the shuttle. In addition, the explained alternate engagement between the two 55 pairs of cooperating, inclined surfaces of the bobbin case 47 and the member 57 results in alternate opening and closing of the gaps 58 and 59, thus permitting the passage therethrough of the forward leg 62 of a non-twisted loop 1 without 60 interference from said member 57.

Fig. 11 discloses a modified shuttle mechanism wherein the shuttle 25a is identical with, and supported in the same manner as, the shuttle 25 in Figs. 2 and 3. The shuttle-driving arm 65 31a is, however, directly mounted on a shaft 71, journaled in the illustrated inclined fashion in a bearing bracket 34a which is in turn suitably mounted on the horn of a lock-stitch sewing machine. In order that the driving fingers 30a 70 of the arm 31a move alternately into driving engagement with the shuttle 25a, and in order that at least one of said driving fingers is in engagement with said shuttle irrespective of the angular position of the latter, the shaft 71 extends in 75 the present instance substantially at right angles

to the plane of the inclined, active surface 39 of the annular cam 38 in Fig. 3. Obviously, any heat-generating sliding friction between the driving lever 31a and an operating cam, such as cam 38 in Fig. 3, is eliminated in this modified 5 shuttle mechanism.

I claim:

1. In a shuttle mechanism, the combination of a rotatably mounted shuttle; a bobbin-case member provided with at least two angularly spaced shoulders; a non-rotatable member having at least two angularly spaced projections; and means carried by the shuttle for supporting said bobbin-case member for rotation about an axis parallel to the shuttle axis and for causing 15 such relative movement between said members during rotation of the shuttle that said projections and shoulders alternately engage each other, said projections being in the path of rotation of said shoulders in the normal direction of 20 rotation of the shuttle.

2. In a shuttle mechanism, the combination of a rotatably mounted shuttle; a bobbin case member provided with at least two angularly spaced shoulders; another non-rotatable member having 25 at least two angularly spaced shoulders; and means carried by the shuttle for supporting said bobbin case member for rotation about an axis parallel to the shuttle axis and for causing such relative movement between said members during 30 rotation of the shuttle that the shoulders of said members alternately engage each other, the shoulders of said other member being in the path of rotation of the shoulders of said bobbin case member in the normal direction of rotation 35 of the shuttle, and the shoulders of at least one of said members being so inclined with respect to the shuttle axis as to resist axial removal of said bobbin case member from said supporting means upon engagement with either shoulder of the 40 other member.

3. In a shuttle mechanism, the combination of a rotatably mounted shuttle having a projecting eccentric pin parallel to the shuttle axis; a bobbin case provided with at least two angularly spaced shoulders, said bobbin case being rotatably supported on said eccentric pin; and at least two stationary and angularly spaced surfaces in the path of rotation of said shoulders in the normal direction of rotation of the shuttle, 50 said eccentric pin rocking the bobbin case during rotation of the shuttle such that said surfaces and shoulders alternately engage each other.

4. In a shuttle mechanism, the combination of a rotatably mounted shuttle; a bobbin-case member provided with at least two angularly spaced shoulders; a non-rotatable member having at least two angularly spaced projections; means carried by the shuttle for supporting said bobbin-case member for rotation about an axis parallel 60 to the shuttle axis and for causing such relative movement between said members during rotation of the shuttle that said projections and shoulders alternately engage each other, said projections being in the path of rotation of said shoulders in the normal direction of rotation of the shuttle and each engaged projection normally resisting the axial removal of said bobbin-case member from said supporting means; and means also carried by the shuttle for directing the thread 65 70 of a loop passing around the rotating shuttle through the gap between each disengaged projection and shoulder.

5. In a shuttle mechanism, the combination of a rotatably mounted shuttle; a bobbin case 75

member; means supporting said member for rotation in said shuttle about an axis parallel to the shuttle axis; and a stationary member, said members having spaced pairs of abutments of which any engaged pair positively prevents rotation of the bobbin case with the shuttle in one direction, and said means causing such relative movement between said members during shuttle rotation in said one direction that said abutment pairs are alternately engaged.

5. In a shuttle mechanism, the combination of a rotatably mounted shuttle; a bobbin case member; means supporting said member for rotation

in said shuttle about an axis parallel to the shuttle axis and for axial movement out of the shuttle; and a stationary member, said members having spaced pairs of abutments of which any engaged pair positively prevents rotation of the bobbin case with the shuttle in one direction and frictionally resists axial movement of the bobbin case from the shuttle, and said means causing such relative movement between said members during shuttle rotation in said one direction that 10 said abutment pairs are alternately engaged. 5

AXEL FOLKE CARLSON.
